AIR CONDITIONING DEVICE

Powel Crosley, Jr., Cincinnati, Ohio, assignor to
 The Crosley Corporation, Cincinnati, Ohio, a
 corporation of Ohio

Application March 26, 1934, Serial No. 716,428

9 Claims. (Cl. 62—140)

The cooling and conditioning of air in buildings by refrigeration entails a number of serious problems. At best the power requirements are high. It has been ascertained that about three horse power are required to cool a room of average size adequately in summer weather such as prevails in the Central States. The problem is further complicated and the power requirements increased by the lack of insulation in most dwellings and public buildings. The special circumstances in each installation must therefore be taken into account for best results, which militates against the use of standardized equipment and increases cost.

Hence, where cooling has been attempted in dwellings, the endeavor has been to cool one room, —say, a bedroom,—or at most only a small number of rooms. Even in such attempts, however, the equipment is preferably of the type which must be built in. This is primarily for the reason that the motor, compressor and condenser of the refrigerating equipment should be located at a point remote from the evaporator, not only to cut down the noise, but also to avoid the effects of the heat developed by the first mentioned apparatus. It will be clear that if the motor, compressor and condenser are located in the same air space with the evaporator, the net result of the operation of the mechanism will be a rise in temperature due to the wattage consumed. This has rendered more difficult the provision of portable units, since such units are not successful unless they have compartments separating the several mechanisms and intake and outlet connections to some other room, or to the out of doors, for the air used in cooling the power devices.

In the light of these problems, my invention has for its several primary objects the following: the provision of a cooling and air-conditioning device, the action of which may be localized to a particular zone of use; hence the provision of a device which may be truly portable, since the segregation of the several parts may be accomplished as between the zone of use and surrounding areas. It is an object of my invention to provide a device of the character to be described, in which the power requirements are low, and in which both the first cost and the running costs are low enough to make the use of the device possible for the average individual.

Briefly in the practice of my invention, I provide in a single unit the elements of a power cooling device, together with means for localizing the condition effect to a definite and relatively

restricted zone. While the utility of my device is not limited thereto, I shall describe it in a preferred embodiment designed for cooling, dehumidifying and conditioning the air immediately surrounding a bed. It will be understood that slight modifications may be made in my exemplary structure to adapt it for cooling any desired localized area.

In the exemplary embodiment I provide a base, preferably mounted upon casters for portability, and bearing a motor, compressor, condenser and associated apparatus. The base also bears a standard adapted to support a canopy for segregating the particular zone of use hereinabove referred to, the canopy, however, being so disposed as not to include the base or the power instrumentalities mounted thereon. The standard also bears, but within the canopy, an evaporator, together with means for collecting and carrying away moisture condensed from the air by the evaporator. The canopy may be positioned above a bed, and the edges thereof tucked in about the mattress if so desired.

I have found that a unit of small size and consuming but little power is adequate to cool and condition the air about a bed or other localized area of similar size. The unit required is of the order of the size of units employed in average refrigerators; but size is not a limitation upon my invention. In this way I have succeeded in providing a truly portable device of low cost such as may be used by the householder of average means, or such as may be employed in hospitals and the like to give comfort to the patients, where the cost of cooling the building would be prohibitive. Moreover, in the form of my invention herein described, the positioning and functioning of the parts is such that no fan is required to circulate air through the evaporator. This makes for very quiet operation.

The objects of my invention, which will be clear from the foregoing or will be understood by those skilled in the art from the detailed description which follows, I accomplish by that certain construction and arrangement of parts of which I shall now describe the aforesaid exemplary embodiment.

Reference is made to the drawings, wherein:

Figure 1 is a top plan view of the canopy and supporting means.

Figure 2 is a side elevation, with the canopy shown in section.

Figure 3 is a detailed view of a portion of the standard, and the evaporator associated therewith.

Figure 4 is a detailed view of the compressor and associated devices mounted upon the base.

Figure 5 is a top plan view of the evaporator.

Figure 6 is an end elevation of the evaporator 5 showing the louvre construction.

The general assembly of my device is best indicated in Figure 2, where 1 indicates a bed, and 2 the base of my device. The base is preferably mounted upon casters 3, and is extended upon one 10 side as shown, in order to give an adequate bearing support for the standard and associated parts. A housing for the motor, compressor and the like is indicated at 4; and the standard member, the upright portion of which is shown at 5, rises substantially centrally of the base. Bracing members 6 may be employed to rigidify the housing. The extended end of the base may conveniently be pushed under the bed, in order to bring the member 5 close to the end thereof.

20 The standard portions of my device may be made of pipe sections, the hollow form of which permits the leading of the several connections to and from the evaporator through the pipe. An elbow 7, preferably having less than a right angled bend, is employed, in connection with certain intermediate members hereinafter to be described, to support a member 8 extending to a substantially central point above the bed. A vertical canopy support 9 is attached by suitable couplings to the member 8, and may bear crossed wooden bars 10. Iron rods 11, connecting the ends of these bars, complete an adequate support for the canopy 12. At one side, an entrance to the canopy may be effected through flaps 12a and 12b slidably mounted upon one of the rods 11.

An evaporator indicated generally at 13, is supported by clamps located on the standard structure within the canopy.

40 The motor and compressor assembly is shown in Figure 4 as built up on a sub-base 14, suspended by springs 15 from suitable supports (not shown) attached directly or indirectly to the base 2. The sub-base carries an electric motor 16, connected by a belt 17 to the driving wheel 18 of a compressor 19. A condenser 20 is shown mounted upon the base 2. A fan 21 may be attached either to the motor or compressor shafts, to cause a circulation of air over the coils of the 45 condenser; and the front portion of the housing 4 may be cut away as shown and fitted with a screen 22 to permit passage of air. The base 2 is of open, frame-like construction permitting circulation of air.

55 The inlet 23 to the compressor is connected to the return lead 24 from the evaporator. This lead passes down preferably inside the standard 5, and is coiled or goose-necked as shown to permit vibration of the sub-base 14 and its associated 60 apparatus. Likewise the high pressure side of the compressor is connected by a goose-necked tube 25 to the condenser 20. The particular type of evaporator feed control employed in my exemplary embodiment, and which is not a limitation 65 upon my invention, is one in which a tube of small diameter is used to feed a controlled amount of refrigerant continuously. This tube is indicated at 26, connected to the condenser through a filter 27, and passing up the standard 70 5. The standard finally contains a tube 28 passing downward to a container 29, which may be suspended from a hook 30 to catch and hold moisture condensed upon the evaporator.

The evaporator and attendant apparatus are 75 shown in Figs. 3, 5 and 6. The elbow 7 supports

a short length of relatively heavy pipe or rod 31 as shown in Fig. 3, to which the evaporator is attached by means of clips 32. A reducing coupling 33 on the arm of the pipe 31 is used to attach the member 8 which is a lighter construction and is used to support the canopy. The evaporator is indicated generally in Figs. 5 and 6, at 10 34. It comprises a coil of tubing and suitable supports preferably divided into two parts, one located on either side of the support 31. The parts are preferably tilted as shown. Since it is the purpose of my invention to provide for the circulation of air, within the canopy, by convection currents, it is necessary to provide below the evaporator, a construction which will permit the 15 passage of air but will entrap any moisture condensed upon the evaporator. Hence I provide, as best shown in Fig. 6, a series of louvre plates 35 reversely bent as shown to provide gutters for the discharge of condensate. It will be observed 20 that the support 31 is tilted at an angle to the horizontal so that the gutters of the louvre plates may feed down into a trough member 36, which in turn empties into a collector cup 37 on the upper end of the tube 28. The feeder tube 26 from the 25 compressor is preferably connected through a fitting 38 to the end of the evaporator and the other end thereof is connected through a tube 39 to a reservoir 40 to which the tube 24 to the compressor is connected and preferably provided with 30 an oil skimming device.

In the operation of my device, the air inside the canopy is cooled and conditioned by convection, the arrows in Fig. 2 indicating the general course of the air currents. It will be noticed that 35 the evaporator is preferably, though not necessarily, located near the foot of the bed so that the cooled air sinks therefrom and spreads out over the lower part of the enclosure. The warm air of respiration has a natural tendency to rise, 40 and therefore further assists the circulation. The material of the canopy need not be of heavy or air tight fabric. A light and relatively porous fabric is sufficient to isolate the cooled zone effectively and has the additional advantage of permitting 45 sufficient bleeding of the air to effect a change thereof from time to time. If, however, a heavier material is employed, it may be found advantageous to provide small screen openings in the canopy such as one at the bottom and near the 50 head of the bed and one near the top of the canopy.

In this way I have provided a device which is portable and is adapted for use in the conditioning of the air in a restricted zone of use. The 55 isolation of this zone by means of the canopy makes it unnecessary to provide outside connections for air to the condenser; and the use of convection currents for the conditioning of the air eliminates the use of a fan and makes for 60 very quiet operation.

Having thus described my invention, what I claim as new and desire to secure by Letters Patent of the United States is:

1. In an air conditioning device a portable base, 65 a cabinet mounted thereon, the high pressure portion of a refrigerating device mounted in said cabinet, a standard associated with said base, means on said standard for supporting a canopy, a canopy so supported and an evaporator supported from said supporting means within said canopy, and a trap for catching and conducting away moisture condensed on said evaporator. 70

2. In an air conditioning device a portable base, a cabinet mounted thereon, the high pres- 75

- sure portion of a refrigerating device mounted in said cabinet, a standard associated with said base, means on said standard for supporting a canopy, a canopy so supported and an evaporator supported from said supporting means within said canopy, and a trap for catching and conducting away moisture condensed on said evaporator, said standard being hollow and connections to and from said evaporator passing through said standard.
3. In an air conditioning device a portable base, a cabinet mounted thereon, the high pressure portion of a refrigerating device mounted in said cabinet, a standard associated with said base, means on said standard for supporting a canopy, a canopy so supported and an evaporator supported from said supporting means within said canopy, and a trap for catching and conducting away moisture condensed on said evaporator, said standard being hollow and connections to and from said evaporator passing through said standard, and means for causing a power forced circulation of air through said cabinet.
4. In an air conditioning device, portable means for isolating an entire zone of immediate personal occupancy, and means located within first mentioned means for cooling said zone and inducing circulation of air therein by convection, said means comprising a cooling device located inside said isolating means and near the top thereof, said isolating means including a canopy of flexible material, and supporting means therefor.
5. In an air conditioning device, portable means for isolating an entire zone of immediate personal occupancy, and means located within said first mentioned means for cooling said zone and inducing circulation of air therein by convection, said means comprising a cooling device located inside said isolating means and near the top thereof, said isolating means including a canopy of flexible material, and supporting means there-
- for, and means for permitting entrance to and exit from said isolating means.
6. In an air conditioning device, portable means for isolating an entire zone of immediate personal occupancy, and means located within said first mentioned means for cooling said zone and inducing circulation of air therein by convection, said means comprising a cooling device located inside said isolating means and near the top thereof, said isolating means including a canopy of flexible material, and supporting means therefor, and means for permitting entrance to and exit from said isolating means, said isolating means having means to permit slow change of atmosphere in said zone.
7. An air cooling and circulating device comprising a receptacle, a cooling device suspended at the upper part of said receptacle, the receptacle being made of flexible material, with means for holding it in its operative position.
8. In an apparatus of the kind described, the combination with a support and an enclosing canopy carried thereby, of a refrigerating unit carried by said support, an air conditioning unit carried by said support and extending therefrom into the upper part of said canopy and having means for cooling and circulating air in said canopy, and refrigerant conducting means connecting said units.
9. In an apparatus of the kind described, the combination with a base, supporting means carried by said base and extending upwardly therefrom, and having a lateral arm, and an enclosing canopy carried by said arm, of a refrigerating unit carried by said base, an air conditioning unit carried by said arm and extending therefrom into said canopy and having means for cooling and circulating air in said canopy, and refrigerant conducting means connecting said units.

POWEL CROSLEY, JR.
